FLYWHEEL MAGNETO

Stanley M. Terry and Bob O. Burson, Longmeadow, Mass., assignors to R. E. Phelon Company, Inc., a corporation of Massachusetts

Filed June 25, 1963, Ser. No. 290,538

6 Claims. (Cl. 310—70)

This invention relates to flywheel type magnetos or the like and has particular reference to the provision of a new and improved flywheel type magneto which is particularly adapted to operation with automatic spark advance.

Small, high output gasoline engines are being applied in increasingly large numbers in a large variety of applications such as, for example, in lawn, garden and farm equipment.

In order to enhance the starting and to improve the high speed operations of such engines, automatic spark advance is being increasingly utilized thereon.

However, when automatic spark advance is applied to conventional magnetos, either the low speed or the high speed voltage output has been found to be inadequate or the advance change over has had to operate at excessively high speed in order to generate adequate voltage after advance with resultant low torque at the lower speeds and loss of operating efficiency of the engine.

An object of the present invention is to provide a new and improved flywheel type magneto which is particularly adapted for operation with automatic spark advance.

Another object of the invention is to provide a new and improved flywheel type magneto of the type set forth which provides adequate ignition voltage both for starting at low cranking speed and for high speed operation and which is designed to advance at relatively low engine speeds to provide optimum engine torque output for accelerating under heavy load.

Another object is to provide a new and improved flywheel type magneto of the type set forth which produces such adequate voltage without the necessity that the advance mechanism be set for excessively high speeds.

Another object is to provide a new and improved flywheel type magneto of the type set forth which is particularly adapted to provide high ignition voltage in any normal designed range of advance, for example, fifteen degrees to twenty-five degrees or more.

Another object of the invention is to provide a new and improved flywheel type magneto of the type set forth which is both simple to apply to engines and economical to manufacture.

Other objects and advantages of the invention will be apparent from the following description taken in connection with the accompanying drawings. It will be understood that changes may be made in the details of construction and arrangement of parts shown and described as the preferred form of the invention has been given by way of illustration only.

Referring to the drawings:

FIG. 1 is a fragmentary top view of a flywheel type magneto embodying the present invention;

FIG. 2 is a sectional view taken on line 2—2 of FIG. 1, looking in the direction of the arrows;

FIG. 3 is a fragmentary bottom view of the device shown in FIGS. 1 and 2; and

FIG. 4 is a schematic view of the electrical system of the apparatus.

Referring more particularly to the drawings wherein similar reference characters designate corresponding parts throughout, the device shown therein comprises a low tension flywheel type magneto having a stator 10 and a rotor 11, said rotor 11 carrying the magnet 13 and the

2

associated pole pieces 14 and being mounted for rotary movement upon the engine crankshaft or shaft 12 which is adapted to be rotated in timed relationship with the engine.

5 The stator 10 is provided with a three legged or poled laminated magnetic structure or core 15 having low tension primary generating coils or windings 16 upon the first two legs thereof in the direction of rotation of the rotor 11, said two windings 16 being connected in series.

Said two coils or windings 16 may be identical or may be tailored for special engine operating requirements.

The capacitor 17 and the breaker 18, which is operated by the cam 19, are connected across the stator windings 16 and the high tension step-up transformer 20 is connected across said breaker 18 and said windings 16 and in parallel with said stator windings 16.

Any conventional means may be used to advance, either mechanically or automatically, the timing of the device and to change the phase relation between the cam 19 and the crankshaft 12. An example of such means is, for example, that disclosed in United States Patent Number 2,806,156 to R. E. Phelon where the breaker cam is connected to the shaft by means of a rotatably adjustable sleeve, which sleeve is adjustable relative to said shaft, such that advance or retardment may be obtained as the speed of the engine increases or decreases.

In the operation of the foredescribed magneto, at starting the magneto operates normally. At low speed operation, the magneto breaks on the reversal of flux in the coil or winding 16 on the middle leg of the laminated magnetic structure 15 carried by the stator 10. During this period, the second or other primary coil 16 is merely in series with said working primary coil 16, and, being open circuited magnetically and having low impedance, it has little effect on the final voltage output of the device.

When the cam 19 is advanced, whether mechanically or automatically, the break occurs on the buildup and less voltage will, of course, be generated in a given primary coil.

40 Thus, the second primary coil 16 on the leading leg of the structure 15, which is connected in series with the center primary coil 16, will generate an equal voltage and, in effect, double the effective induced voltage in the total primary circuit as, in the advanced position, the two windings 16 upon the laminated structure or core 15 will be generating simultaneously.

From the foregoing, it will be seen that we have provided a new and improved high output flywheel type magneto with automatic spark advance, and high output at all speeds of the cam.

55 From the foregoing, it will be seen that we have provided new and improved means for accomplishing all of the objects and advantages of the invention.

We claim:

1. In a flywheel magneto having a stator and a rotor, a magnet carried by said rotor, pole shoes carried by said rotor and operatively associated with said magnet, a three legged laminated magnetic structure on said stator and operatively positioned thereon with regard to said magnet on said rotor, windings upon the first two legs of said laminated magnetic structure to be engaged by said rotor magnet and associated pole shoes during the operation of the magneto, said windings being connected in series, and a transformer connected in parallel with said windings on said magnetic structure.

60 2. In a flywheel magneto having a stator and a rotor, said rotor being mounted for rotary movement upon a crankshaft, a magnet carried by said rotor, pole shoes carried by said rotor and operatively associated with said magnet, a three legged laminated magnetic structure on said stator and operatively positioned thereon with regard to said magnet on said rotor, windings upon the first two

legs of said laminated magnetic structure to be engaged by said rotor magnet and associated pole shoes during the operation of the magneto, said windings being connected in series, a transformer connected in parallel with said windings on said magnetic structure, and a breaker connected across said windings, a cam operatively connected to and operating said breaker, and means for changing the phase relationship between said cam and said magneto crankshaft.

3. In a flywheel magneto having a stator and a rotor, a magnet carried by said rotor, pole pieces carried by said rotor and operatively associated with said magnet, a three poled laminated magnetic structure on said stator and operatively positioned thereon relative to said magnet on said rotor, windings upon the first two poles of said laminated magnetic structure to be engaged by said rotor magnet and associated pole pieces during the operation of the magneto, said two windings being connected in series, and a transformer connected in parallel with said stator windings.

4. In a flywheel magneto having a stator and a rotor, said rotor being mounted for rotation upon a crankshaft, a magnet carried by said rotor, pole pieces carried by said rotor and operatively associated with said magnet, a three poled laminated magnetic structure on said stator and operatively positioned thereon relative to said magnet on said rotor, windings upon the first two poles of said laminated magnetic structure to be engaged by said rotor magnet and associated pole pieces during the operation of the magneto, said two windings being connected in series, a transformer connected in parallel with said windings, a breaker connected across said windings, a cam operatively connected to and operating said breaker, and means for changing the phase relationship between said cam and said magneto crankshaft.

5. In a flywheel magneto having a stator and a rotor, a magnet carried by said rotor, pole pieces carried by said rotor and operatively associated with said magnet,

5 a three legged laminated magnetic structure on said stator and operatively positioned thereon relative to said magnet on said rotor, windings upon the first two legs of said three legged structure to be engaged by said rotor magnet and associated pole pieces during the operation of the magneto, said two windings being connected in series, and a high tension transformer connected in parallel with said windings.

6. In a flywheel magneto having a stator and a rotor, 10 said rotor being mounted for rotary movement upon a crankshaft, a magnet carried by said rotor, pole pieces carried by said rotor and operatively associated with said magnet, a three legged laminated magnetic structure on said stator and operatively positioned thereon relative to said magnet on said rotor, windings upon the two leading legs of said three legged laminated structure, said two windings being connected in series, a high tension transformer connected in parallel with said windings, a breaker connected across said windings, a cam operatively connected to said breaker such as to operate said breaker, and means for changing the phase relationship between said cam and said magneto crankshaft.
